UNITED STATES PATENT OFFICE

151,948

DESIGN FOR AN AIRPLANE

Pablo M. Acosta, San Gabriel, Calif.

Application October 21, 1947, Serial No. 142,043

Term of patent 7 years

(Cl. D71—1)

To all whom it may concern:

Be it known that I, Pablo M. Acosta, a citizen of the United States, residing at San Gabriel, in the county of Los Angeles and State of California, have invented a new, original, and ornamental Design for an Airplane, of which the following is a specification; reference being had to the accompanying drawing, forming a part thereof.

Figure 1 is a top plan view of an airplane, embodying my new design;

Figure 2 is a side elevation thereof; and

Figure 3 is a front end view.

I claim:

The ornamental design for an airplane, as shown.

PABLO M. ACOSTA,
